UNITED STATES PATENT OFFICE.

NICHOLAS DREW, OF MORA, MINNESOTA.

POTATO-DIGGER.

1,096,610.

Specification of Letters Patent.

Patented May 12, 1914.

Application filed January 23, 1914. Serial No. 813,950.

To all whom it may concern:

Be it known that I, NICHOLAS DREW, a citizen of the United States, residing at Mora, in the county of Kanabec and State 5 of Minnesota, have invented certain new and useful Improvements in Potato-Diggers, of which the following is a specification, reference being had to the accompanying drawings.

10 This invention relates to new and useful improvements in agricultural implements and more particularly to a device known as a potato digger and the primary object of the invention is to provide an improved device of this character which will be most efficient in carrying out the purpose for which the same is designed.

15 A further object of the invention resides in providing a digger composed of a gang of teeth, the same being formed on the curved ends of a plurality of longitudinal shanks or bars carried on the device and a still further object resides in providing a plurality of teeth, certain of which are of greater 20 length than others and the effective or engaging ends of which are disposed in a plane arranged at an obtuse angle with respect to the longitudinal plane of travel of the device.

25 30 A still further object of the invention resides in providing a device which is simple and durable in construction, inexpensive to manufacture and one which will be very efficient and useful in operation.

35 With these and other objects in view, the invention consists in the novel features of construction, combination and arrangement of parts as will be hereinafter referred to and more particularly pointed out in the 40 specification and claims.

45 In the accompanying drawing forming a part of this application, Figure 1 is a plan view of a device constructed in accordance with my invention; and Fig. 2 is a side elevation thereof.

50 In describing my invention, I shall refer to the drawing in which similar reference characters designate corresponding parts throughout the several views and in which—

55 1 indicates a main bar, to the rear face of which is secured a strip or plate 2, one end of which is bent angularly and rearwardly to form an extension 3. Secured to the outer face of the strip 2, in overlapping relation to one another, are the angularly bent ends 4 of the rearwardly extending arms or

bars 5 and the means which secured said angularly bent ends to the plate or strip 2, also secured the latter to the main bar 1. As many arms or bars 5 may be provided as 60 are found desirable, the same being disposed parallel to one another and directed in a plane angular to the longitudinal plane of travel of the device. The rear ends of said arms are curved downwardly and forwardly, 65 as shown at 6 to provide substantially harrow teeth. The bars or arms 5 are increased in length toward one side of the device and the teeth formed at the lower ends of the curvatures of the arms at the side of the 70 device having the shorter arms, are of greater length than the teeth formed on the remaining arms.

Carried on the extension 3 and directed substantially parallel to the main bar 1, is a 75 plate or strip 7 having a plurality of slots 8 therein through which are guided the arms or bars 5. This strip or plate forms a guiding and bracing means for the arms or bars in the application of the device to use.

Secured to the main bar 1, are the ends of a pair of rods 9, the latter being also secured to the plate or strip 7 to brace the latter and continuing from these rods or bars are the upwardly and rearwardly extending handle 85 members 10. Through these handle members the teeth may be forced into engagement with the surface of the ground as the device is propelled thereover.

Projecting from the outer ends of the 90 main bar 1, are the bars or strips 11 which converge toward one side of the device, forward of the main bar and have the draft securing means 12 adjustably attached thereto. Carried on one of these bars 11, is a depending arm 13, to the lower end of which is swiveled a colter 14, the purpose of the latter being obvious.

From the foregoing description of the construction of my improved device, the 100 manner of applying the same to use and the operation thereof will be readily understood and it will be seen that I have provided a device which is simple and durable in construction, inexpensive to manufacture 105 and one which will be very efficient and useful in operation.

While I have particularly described the elements best adapted to perform the functions set forth, it is obvious that various 110 changes in form, proportion and in the minor details of construction may be resort-

ed to without departing from the spirit or sacrificing any of the principles of the invention.

Having thus described this invention,
5 what I claim is:

1. A device of the class described comprising a main bar, a plurality of arms secured thereto and extending rearwardly thereof, the rear ends of said arms being curved 10 downwardly and forwardly to provide teeth, means in connection with said bar to draw the same forwardly, said bar being disposed at an inclination to the line of travel thereof, bracing means for the aforesaid arms, and 15 handle members in connection with said bar and bracing means to force the teeth into the surface of the ground.
2. A device of the class described comprising a main transverse bar, means in connection therewith to draw the same forwardly, said bar being disposed at an inclination to the line of travel thereof, a plurality of spaced longitudinally extending arms having the forward ends thereof bent 20 angularly and secured in overlapping relation to one another on the rear face of said main bar, the rear ends of said arms being bent downwardly and forwardly to form teeth, bracing means for said arms, and 25 handle members in connection with said bar and bracing means to force the teeth downwardly into engagement with the surface of the ground.
3. A device of the class described comprising a main bar, means in connection therewith to draw the same forwardly, said bar being disposed at an inclination to the line of travel thereof, a plurality of spaced longitudinally extending arms having the forward ends thereof bent 30 angularly and secured in overlapping relation to one another on the rear face of said main bar, the rear ends of said arms being bent downwardly and forwardly to provide teeth, a strip also secured to the rear face of said main bar 35 by the means securing the forward ends of said arms thereto, the one end of said strip being bent rearwardly to extend parallel with said arms, a plate secured at its one end to the last mentioned angularly bent portion 40 of said strip and disposed parallel to the main bar, said plate being provided with a plurality of slots receiving the aforesaid arms therethrough, whereby to guide and brace the latter in position, and a pair of additional arms secured to said main bar and plate, the rear ends thereof being disposed 45 upwardly and rearwardly and designed to form handles.

In testimony whereof I hereunto affix my 50 signature in the presence of two witnesses.

NICHOLAS DREW.
